UNITED STATES PATENT OFFICE

RALPH E. HYDE, OF CLEVELAND, OHIO, ASSIGNOR TO THE OSTER MFG. COMPANY, OF CLEVELAND, OHIO, A CORPORATION OF OHIO

DIESTOCK

Application filed March 12, 1928. Serial No. 261,014.

The present invention relates, as indicated, to a stamped receding-chaser type die stock. The invention is directed to a novel and advantageous die stock of the character described, and the primary object of the invention is to provide an inexpensive die stock of the character described formed from sheet metal. To the accomplishment of the foregoing and related ends, said invention, then, 10 consists of the means hereinafter fully described and particularly pointed out in the claims.

The annexed drawing and the following description set forth in detail one method 15 and one product exemplifying my invention, such disclosed procedure and product consisting, however, but several of various applications of the principle of my invention.

In said annexed drawings:

20 Fig. 1 is an elevation, partly in section upon the line 1—1 of Fig. 2; Fig. 2 is a bottom plan view of the same; Fig. 3 is a section taken substantially upon the line 3—3 of Fig. 1, looking in the direction of the arrows; 25 and Fig. 4 is a transverse section of a modification.

Referring more particularly to the drawings, it will be seen that the reference numeral 1 indicates a tubular member provided 30 adjacent its upper end with a shoulder 2 separating the upper end 3 of the tubular member 1 from the lower restricted end 4 thereof. Adjacent the lower end of the section 4, there is provided a second internal 35 shoulder 5 defining a still further constricted section 6 which is interiorly threaded as at 7. A second tubular member 8 is exteriorly threaded as at 9 and is formed at its one end with an external annular flange 10. The 40 threads 9 are adapted to cooperate with the threads 7, said tubular member 8 being of such diameter as to be telescoped within the tubular member 1.

45 The member 1 is preferably formed from flat sheet metal by rolling or stamping the shoulders 2 and 5 and then forming the stamped blank into a tube. The tubular member 8, may be, and preferably is, similarly 50 formed, the flange 10 being formed by rolling

or stamping before the blank is formed into a tube. An annular ring 11 which is substantially L-shaped in cross section rests upon the shoulder 2 and secures in place a collar 12, the latter being received between 55 the ring 11 and the wall of the portion 3 of the tubular member 1. Tapped apertures 13 are adapted to receive thumb screws 14 for clamping work in position in said stock.

To the flange 10 of the tubular member 8 60 there is secured a composite member comprising a pair of plates 15 and 16. The plate 15, formed from sheet metal is provided with a substantially central aperture 17 and with a plurality of rebent portions 18 forming 65 grooves 19 open at their upper edges as at 20. Said plate 15 is further provided at its opposite ends with semi-cylindrical portions 21 opening in the same plane with the open edges 20 of the grooves 19.

The plate 16 is provided with a substantially central aperture 22, adapted to register with the aperture 17, and is further formed at its opposite ends with semi-cylindrical portions 23 adapted to mate with the portions 21 to form cylindrical handle sockets. In 70 assembling the die stock, the plates 15 and 16 are secured to each other and to the flange 10 by means of rivets 24, or the like, it being noted that the plate 16 closes the open upper 75 edges 20 of the grooves 19.

A pair of bearing rings 25 and 25' are received upon the external surface of the portion 6 of the tubular member 1, said ring 25' being supported by a slight shoulder 26, and a collar comprising a pair of plates 28 and 29 is journalled on said section 6 between 80 said collars 25 and 25'. The member 29 is provided with a peripheral downturned 85 flange 30 which snugly surrounds the member 28. The members 28 and 29 are pierced as at 32 and 31, respectively, to receive an end of a post 33, said end being upset to secure 90 the post in position. It will be noted that 95 one post 33 is provided for each of said grooves 19. One face 34 of each of said posts 33 is formed as a cam, and the end of each of said posts extends through an aperture 35 in the rebent portion 18, thus traversing the 100

groove 19, the face 34 of the post being inwardly directed. It will be seen that the plate 16 cooperates with the rebent portions 18 to transform the grooves 19 into chaser-receiving sockets. A chaser 36 is received in each of said sockets with its outer end in contact with the cam face 34 of a post 33, the cutting edge 37 of each cam extending into the aperture 17. The cylindrical handle sockets are interiorly threaded as at 56.

In operation, a piece of work is inserted in the stock and is clamped therein by means of the thumb screws 14, the tubular member 8 having been rotated to back the same off to its most extended position. The work having been inserted in the stock, the tubular member 8 is rotated in the opposite direction, whereby it is advanced into the tubular member 1 through the agency of the threads 7 and 9. The tubular member 1 is held stationary by the clamping engagement of the thumb screws 14 upon the work, but the collar 28, 29 is free to rotate with respect to the tubular member 1. It will be readily apparent that, as the tubular member 8 advances into the tubular member 1, the cam faces 34 of the posts 33 will allow the dies 36 to recede from their projection into the aperture 17, and that the result of the operation of the present die stock will be a tapered thread.

In the modification disclosed in Fig. 4, the tubular member 38 is, in all particulars, similar to the tubular member 1. The tubular member 39, however, is provided with a flange 40 which takes the place of the plate 16 in the modification illustrated in Fig. 1. A plate 41 formed with rebent portions 42 providing grooves 43 is secured to said flange 40 by means of rivets, or the like 44, the flange 40 closing the open upper edges of said grooves 43. A pair of plates 45 and 46 are journaled upon said tubular member 38 between bearing rings 47 and 48, and said plates 45 and 46 are pierced as at 49 for the accommodation of an end of each of a plurality of cam posts 50, each of said posts being provided with a cam face 51. The flange 40 is apertured as at 52 and the rebent portions are apertured as at 53 for the accommodation of said posts 50.

A further difference between the modification now under discussion and that disclosed in Fig. 1 lies in the fact that the handle sockets are formed by the plates 45 and 46, the plate 45 being provided with oppositely disposed semicylindrical portions 54, while the plate 46 is formed with mating oppositely disposed semicylindrical portions 55. The portions 54 and 55 cooperate to form cylindrical handle sockets which are interiorly threaded as at 56.

The operation of the modification disclosed in Fig. 4 is identical with that of the modification illustrated in Fig. 1, the only dif-

ference being that the tubular member 39, instead of being directly rotated by the handles, is rotated through the engagement of the cam posts 50 in the apertures 52 and 53.

Other forms may be employed embodying the features of my invention instead of the one here explained, change being made in the form or construction, provided the elements stated by any of the following claims or the equivalent of such stated elements be employed, whether produced by my preferred method or by others embodying steps equivalent to those stated in the following claims.

I therefore particularly point out and distinctly claim as my invention:

1. In a device of the class described, a tubular element, a second tubular element threadedly telescoped in said first tubular element and projecting therefrom, a flange on the projecting end of said second tubular element, a member secured to said flange and formed to provide a guideway for a die, a shoulder on said first tubular element facing said flange, a member journaled on said first tubular element and backed by said shoulder, and a cam pin secured to said last-mentioned member and extending transversely through said guideway, one of said members being formed to provide a pair of oppositely opening sockets at substantially diametrically opposed points on its periphery.

2. In a device of the class described, a tubular element, a second tubular element threadedly telescoped in said first tubular element and projecting therefrom, a flange on the projecting end of said second tubular element, a composite element secured to said flange and comprising a plate and a second plate, means on said second plate forming a guideway for a die, and means on said first plate cooperating with means on said second plate to form a substantially cylindrical socket projecting from the periphery of said composite member.

3. In a device of the class described, a tubular element, a second tubular element threadedly telescoped in said first tubular element and projecting therefrom, a flange on the projecting end of said second tubular element, a composite element secured to said flange and comprising a plate and a second plate, and means on said first plate cooperating with means on said second plate to form a substantially cylindrical socket projecting from the periphery of said composite member.

4. In a device of the class described, a tubular element, a second tubular element threadedly telescoped in said first tubular element and projecting therefrom, a flange on the projecting end of said second tubular element, a composite element secured to said flange and comprising a plate and a second plate, means on said second plate forming a guideway for a die, means on said first plate

cooperating with means on said second plate to form a substantially cylindrical socket projecting from the periphery of said composite member, and a plurality of fastening elements passing through said flange and said plates to hold said plates in assembled relation to each other and to said flange.

Signed by me this 5th day of March, 1928.
RALPH E. HYDE.
